Case "B"

Elphinston Note

Letters Patent.

The checkerels referred to in these Letters Patent and working part of the same, containing a description in the name of the said Elphinston of his improvement, in the construction and adjustment of the brick forming the flue employed in confining combustion to the base of the fuel contained in an anthracite coal stove.

Case "C" to B

Specification of an improvement made in the construction and adjustment of the brick forming the flue employed in confining combustion to the base of the fuel contained in anthracite coal stoves.

Whereas, in coal stoves, the front brick of the flue by which the outlet for flame, at the bottom of the chamber of combustion is formed, usually burns away sooner than any other brick; and whereas, in replacing the same inconveniences has arisen from the confinement of the end of the flue in the side walls of said chamber. Therefore an improvement has been introduced and the same having been tested and perfected by repeated experiments, is now intended to be introduced into general use - which improvement consists, in making use, in constructing the front of said flue, of brick, or slabs of other incombustible material which extend merely across the caliber of the chamber of combustion, in place of brick a sheet of iron extending beyond and entering the side walls by which said caliber is formed - after so making use, in constructing the end of said flue of right and left joint brick, from the internal face of which brick a tongue projects inward at the proper place, one of

(12)

The further form and the proper extent for securing and sustaining in place the brick forming said front flue - in such manner that the same shall make a good fit and at the same time be removable at pleasure, without disturbing any other brick, which will be the more easily effected, if a rabbit in brick be also projected from the right and left jamb of said flue, for the ends of the brick, (forming said front of flue) when in place to rest against. It is to be understood, however, that those rabbits may when preferred, be projected in iron from the side plates. For further information reference may be had to the drawing hereunto appended. Summary. —

The improvement herein contemplated consists in providing for removing and restoring the front of the interior flue, aforesaid, without disturbing the remainder of the brick or stonework - By so shortening the brick of which said front is formed, that the same will freely enter the calibre of the chamber of combustion; and by projecting brackets or tresses from the right and left jamb brick of said flue, for the front brick thereof to stand on; - and also a rabbit for the ends of the same to rest against - except where such rabbit is otherwise provided by a projection in iron from the side plates.

I therefore claim as my invention and improvement, the providing for removing and restoring the front of flue of said by shortening the brick or other slabs of which the same is composed, so that they will freely enter the calibre of the chamber, and by projecting from the right and left jamb brick, the requisite tress or other fixture for sustaining and confining the same in place as aforesaid, together with the uses to which said improvement has been or may hereafter be applied in stoves or furnaces.
